UNITED STATES PATENT OFFICE.

CARL D. BROWN, OF HOPEDALE, MASSACHUSETTS, ASSIGNOR TO DRAPER CORPORATION, OF HOPEDALE, MASSACHUSETTS, A CORPORATION OF MAINE.

FILLING-REPLENISHING LOOM.

1,350,640.

Specification of Letters Patent. Patented Aug. 24, 1920.

Application filed October 15, 1919. Serial No. 330,742.

To all whom it may concern:

Be it known that I, CARL D. BROWN, a citizen of the United States, and a resident of Hopedale, in the county of Worcester and State of Massachusetts, have invented an Improvement in Filling-Replenishing Looms, of which the following description, in connection with the accompanying drawings, is a specification, like characters on the drawings representing like parts.

The invention to be hereinafter described relates to filling replenishing looms, and more particularly to the means for insuring control of the filling leading from the filling carrier or bobbin which is to be ejected.

It is the usual practice in filling replenishing looms to part the filling between the cloth selvage and shuttle when the filling is to be replenished, but since the parting means has usually acted upon the filling near the entrance to the shuttle-box, a long trailing end of filling thread has extended from the filling carrier or bobbin in the shuttle, through the side delivery eye of the shuttle, and longitudinally of the shuttle box. This piece of filling thread, which may be termed the "trailing end" is intended to be withdrawn from between the shuttle and the shuttle-box and backward through the side delivery eye, when the depleted filling carrier or bobbin is ejected from the shuttle. Should the trailing end fail to be withdrawn, as above stated, it is liable to be carried into the shed on a subsequent pick and produce a defect in the cloth, and various means have been provided for making more sure the withdrawal of the trailing end.

The shuttle-box is usually wider at the entrance end than at its closed outer end, and the consequence is that the trailing end, after being parted between the shuttle and the cloth selvage, is liable to drop downwardly between the shuttle and adjacent wall of the shuttle-box and be pinched between them, with the result that as the filling carrier or bobbin is ejected, the trailing end will be broken, leaving a small piece pinched between the shuttle and shuttle-box, which may eventually find its way into the shed and injure the quality of the cloth woven.

One of the objects of the present invention, therefore, consists in means for preventing the trailing end from being pinched between the shuttle and the wall of the shuttle-box and to hold it elevated yet with permissive

movement longitudinally of the shuttle and through the shuttle eye as the filling carrier or bobbin is ejected.

Other objects of the invention, in addition to the above, will hereinafter be referred to in connection with the accompanying drawings which show one good practical form of the invention.

In the drawings:

Figure 1 is a plan view of portions of the loom at the replenishing side, many of the parts being omitted as unnecessary to make clear the invention;

Fig. 2 is a detail perspective view looking from the rear of a shuttle box containing the present invention;

Fig. 3 is a cross section on the line 3—3 of Fig. 1;

Fig. 4 is a detail showing one form of means for holding the bristles or tufts in fixed position, but with capacity for adjustment.

The general construction and mode of operation of the loom in which this invention may be advantageously employed, is well understood by those skilled in the art and needs no detailed illustration or description. The loom frame and the filling supplying mechanism, together with the usual hopper, are not here illustrated since they have no special connection with the invention itself.

The lay 1 may be of usual construction and provided with the shuttle-box 2 at the filling replenishing side of the loom, in which the picker 3 may operate to "pick" the shuttle 4. The shuttle box 2, as usual, is provided with an opening at its lower surface through which may be ejected the filling carrier 5 contained in the shuttle 4.

In the present instance of the invention, the front wall 6 of the shuttle box is adjustably secured to the lay by the bolts 7 which pass through the slotted lugs 8 connecting the front wall 6 of the shuttle box with the lay. At its entrance end the front wall of the shuttle box is flared outwardly somewhat, as indicated at 9, to thereby provide a widened or enlarged entrance end to permit the shuttle to surely enter the shuttle box even though it may be deviated somewhat from its direct path during the picking operation.

The inner surface of the front wall 6 of the shuttle-box is provided with a frictional

substance, such as leather or similar material 10, to furnish frictional resistance to the shuttle as it moves to the outer end of the box, and assist in bringing it to rest.

- 5 The shuttle 4 has the side delivery eye 11 through which the filling leading from the filling carrier 5 in the shuttle passes, and extending longitudinally of the shuttle from the side delivery eye, is a groove 12 in which 10 it is desirable that the filling thread 13, Fig. 3, may lie when the shuttle is in the replenishing box. Obviously, if the filling thread 13 which extends from the side delivery eye to the entrance of the shuttle box 15 or the point where the filling end has been parted between the cloth selvage and shuttle, is maintained in the groove 12, it will not be pinched between the inner surface of the front wall of the shuttle-box and the outer 20 surface of the side wall of the shuttle, and may readily be withdrawn backwardly through the shuttle delivery eye when replenishment of filling is effected.
- When the filling is parted between the 25 cloth selvage and the shuttle, however, the terminal portion of the trailing end is liable to drop downwardly between the shuttle and the adjacent front wall of the shuttle-box, and as the filling end is withdrawn during 30 the replenishing operation, the terminal end portion of the filling thread is liable to be pinched between the shuttle and the wall of the shuttle-box unless means is provided to direct the trailing end into the longitudinal 35 groove 12 of the shuttle.

The front wall 6 of the shuttle-box is provided with a series of tufts 14 which may be formed of suitable frictional material for holding the filling thread. In the present 40 instance these tufts are formed of bristles and are secured to the front wall of the shuttle-box in line with the longitudinal groove 12 of the shuttle when the latter is in the replenishing box. The effect of this 45 is that the tufts 14 serve to hold the filling thread or trailing end in the groove 12 of the shuttle, and as the trailing end is withdrawn, these tufts, and more particularly the one at the entrance portion of the 50 shuttle-box, will direct the trailing end upwardly into the groove so that it may be readily withdrawn from the shuttle eye and follow the ejected filling carrier.

In practice it is found desirable to provide 55 a series of the tufts or bristles to effectively hold and position the trailing end of filling in the groove of the shuttle. In the present instance three of these are indicated, one near the entrance of the shuttle- 60 box, one near the closed or outer end of the shuttle-box adjacent the delivery eye of the shuttle, and another intermediate the two, the construction being such that as the filling carrier or bobbin is ejected from the 65 shuttle, the trailing end will be positioned

in the longitudinal groove of the shuttle by the series tufts or bristles secured to the front wall of the shuttle-box.

In the present instance, the tufts or bristles 14 are inclosed in a tube 15 which is 70 passed through the lug 16 and the front wall of the shuttle-box. A set screw 17 serves to hold the tube 15 in adjusted position, whereby the tufts or bristles may be adjusted more or less inwardly relative to the 75 shuttle-box in order to properly adapt them to perform their intended purpose. By providing a number of fixed tufts or bristles on the front wall of the shuttle-box in line with the longitudinal groove 12 of the 80 shuttle, the trailing end of the filling may not only be positioned in the longitudinal groove of the shuttle when the shuttle is boxed, but be maintained in such groove to facilitate its ready removal from between 85 the shuttle and adjacent wall of the shuttle-box as the filling carrier or bobbin is ejected from the shuttle.

Any usual or well-known form of filling parting means may be employed, but in the 90 present instance of the invention the shuttle feeler 18 carries the parting means 19, both of said members being moved rearwardly into operative position, as usual in this type of looms when call for filling replenishment 95 is made. If desired, the shuttle feeler 18 may be provided with clamping means to clamp the filling thread a leading from the cloth selvage, as indicated in Fig. 1, and carry such end of filling into position to 100 be parted by the temple thread cutter 20.

Claims:

1. In a filling replenishing loom, the combination of the lay and shuttle-box, a shuttle having a side delivery eye and a 105 groove extending from said delivery eye longitudinally along the exterior side wall of the shuttle, and a series of tufts secured to the side of the shuttle-box at intervals and in position to enter the longitudinal groove 110 in the shuttle when the latter is boxed acting to hold the filling thread in the groove, and means for adjustably securing the series of tufts in position.

2. In a filling replenishing loom, the combination of the lay and shuttle-box, a shuttle having a side delivery eye and a groove extending from said delivery eye longitudinally along the exterior side wall of the shuttle, and a series of tufts secured to the 120 side of the shuttle-box at intervals and in line with the longitudinal groove in the shuttle when the latter is boxed acting to hold the filling thread in the groove.

3. In a filling replenishing loom, the combination of the lay and shuttle-box, a shuttle having a side delivery eye and a groove extending from said delivery eye longitudinally along the side of the shuttle, and a 125 series of tufts formed of bristles extending 130

into the shuttle-box adjacent both ends thereof and in line with the shuttle groove to hold the filling thread in said groove when the shuttle is boxed.

- 5 4. In a filling replenishing loom, the combination of the lay and shuttle-box, a shuttle having a groove extending from the delivery eye longitudinally along the exterior side wall thereof, a tuft secured to the 10 shuttle-box near the entrance thereof, and a tuft secured to the shuttle-box near the closed or outer end thereof, said tufts positioned to extend into said groove and to engage and hold filling thread in the longitudinal groove of the shuttle when the latter 15 is boxed.
5. In a filling replenishing loom, the combination of the lay and shuttle-box, a shuttle for containing a filling carrier and provided 20 with a groove extending longitudinally from the side delivery eye along the exterior side wall of the shuttle, and thread holding means extending from the side wall of the shuttle-box adjacent the entrance and closed 25 ends thereof for frictionally holding the filling thread in the shuttle groove when the shuttle is boxed.
6. In a filling replenishing loom, the combination of the lay and shuttle-box, a shuttle

having a side delivery eye and a groove extending from said delivery eye longitudinally along the exterior side wall of the shuttle, a series of bristles secured in fixed position adjacent the entrance to the shuttle-box, a series of bristles secured in fixed position adjacent the opposite end of the shuttle-box, and a series of bristles secured in fixed position intermediate the other two, said series of bristles arranged to retain the filling thread in said groove when the shuttle 40 is boxed.

7. In combination with a loom provided with a lay having a shuttle-box and a shuttle therein containing filling thread, means for preventing the trailing end of said filling thread when parted near the selvage from becoming wedged between the shuttle and a wall of the shuttle-box, comprising a longitudinally extending groove formed in an outer wall of said shuttle and positioned to have the filling thread laid therein by the travel of said shuttle, and tufts mounted to extend into said groove when the shuttle is boxed to hold the filling thread in said groove.

In testimony whereof, I have signed my name to this specification.

CARL D. BROWN.
